UNITED STATES PATENT OFFICE.

JAMES F. KELLY, OF BROOKLYN, NEW YORK.

DESIGN FOR A BADGE.

SPECIFICATION forming part of Design No. 16,953, dated October 26, 1886.

Application filed July 6, 1886. Serial No. 207,381. Term of patent 3½ years.

To all whom it may concern:

Be it known that I, JAMES F. KELLY, a citizen of the United States, and a resident of the city of Brooklyn, in the county of Kings and State of New York, have invented and produced a new and original Design for a Badge, of which the following is a specification, reference being had to the accompanying drawing, forming a part thereof, the figure shown being

5 a plan view of the same.

The leading features of my design consist in a circular center field surrounded by a ribbon or garter, with a buckle overlapping and holes therein, the said garter or ribbon having also 15 an edge or border, all of contrasting shades, as shown. Said center field is then so placed upon the center of a Roman cross as to display only a portion of the outer ends of the

four arms of the cross, the longest end being at the bottom of the center field, and more 20 thereof thus appearing. The arms of the cross also have an edge or border. In the center of the field embraced by the ribbon or garter is delineated a heart pierced perpendicularly by an anchor, only the cross-bar and fluke ends 25 of the anchor being displayed.

I claim—

The design for a badge, consisting of the Roman cross, the circular center field bearing thereon a heart pierced by an anchor and surrounded by a ribbon or garter, substantially 30 as shown and described.

JAMES F. KELLY.
